UNITED STATES PATENT OFFICE.

WESLEY G. NICHOLS, OF CHICAGO HEIGHTS, ILLINOIS, ASSIGNOR TO EDGAR ALLEN
AMERICAN MANGANESE STEEL COMPANY, OF AUGUSTA, MAINE, A CORPORATION
OF MAINE.

DRIVING-PINION FOR ROLLING-MILLS.

1,072,488.

Specification of Letters Patent. Patented Sept. 9, 1913.

Application filed September 27, 1911. Serial No. 651,637.

To all whom it may concern:

Be it known that I, WESLEY G. NICHOLS, a citizen of the United States, and a resident of Chicago Heights, in the county of 5 Cook and State of Illinois, have made and invented certain new and useful Improvements in Driving-Pinions for Rolling-Mills, of which the following is a specification.

My invention relates to an improvement 10 in driving pinions especially designed for severe service such for instance as driving the rolls in rolling mills, the object thereof being to provide a pinion in which the gear teeth are formed upon a sleeve separate 15 from and secured to the driving shaft, instead of being formed integrally with a section of the shaft through which the rolls, or similar devices, are driven, as has usually been the case. This feature of construction 20 enables me to form the driving shaft itself, or a section thereof, from wrought metal especially adapted for that purpose, such as forged nickel steel, and to form the sleeve carrying the gear teeth, which 25 must necessarily be formed from cast metal, from manganese steel, a material possessing qualities of toughness and hardness to a degree rendering it especially well adapted for use in pinions of this character.

30 In order to secure a pinion having teeth of manganese steel, the pinion itself, and a section of the driving shaft have been commonly formed as a single integral casting, notwithstanding the fact that such steel is 35 not considered the best metal from which to form the shaft. Such castings have been difficult to make, and unduly expensive, and open to the objection that defects not readily detected, and hard to avoid, often cause the 40 rejection, or failure in use, of an exceedingly expensive casting.

In the practice of my invention, the difficulties above enumerated are avoided, and the portion to be cast from manganese steel 45 is so simplified in form as to be more readily manufactured. The weight thereof is greatly reduced, and the driving shaft formed from a material capable of being forged, thus reducing the cost of the pinion 50 as a whole, which is considered as including a section of the driving shaft, and rendering it better adapted for the purpose for which it is designed.

With the objects of invention above enumerated in view, my invention consists in

the improved driving pinion hereinafter described and claimed, and illustrated in the drawing accompanying and forming a part of this application.

In the drawing wherein the preferred embodiment of my invention is illustrated; Figure 1 is a view partly in side elevation and partly in section showing my improved driving pinion, and, Fig. 2 is a view showing a section upon a transverse plane indicated by the line 2—2, Fig. 1, looking to the left.

Referring to the drawing 3 represents part of a section of a driving shaft and 4 an enlarged portion thereof circular in 70 cross-section upon which a shell 5 is placed, which shell has gear teeth 6, formed upon its periphery, the number, arrangement, and form of such teeth being a matter of design and determined by the particular service for 75 which the pinion is intended. The shell 5 is secured to the enlarged portion 4 of the shaft in part by friction between the two, and in part by keys 7.

The driving shaft 3 is formed from 80 wrought metal such as nickel steel, and is given the required shape and size preferably by forging processes, the result being a shaft well adapted to withstand the torsional stresses met with in heavy service. 85

The shell 5 and gear teeth 6 are formed from cast metal, such as manganese steel, the proper form being thus imparted to the teeth without machining the same, the material specified resulting in teeth that are 90 extremely tough and hard, and which are especially well adapted to endure and give long and satisfactory service when used to drive the rolls in rolling mills. The shell 5 is preferably cored internally, as shown at 95 8, in order to reduce the amount of metal therein and to provide for a more uniform thickness throughout the same.

Having thus described and explained my invention I claim and desire to secure by 100 Letters Patent:—

1. Driving means comprising a wrought metal shaft and an annular shell continuous throughout its circumference secured in place thereupon; said shell being formed 105 from cast manganese steel and having a series of gear teeth upon its periphery, and having also a series of recesses extending outward from said shaft into the body of the shell and located in line with the teeth afore- 110

said, each of said recesses having a single opening leading thereinto.

2. An annular shell continuous throughout its circumference formed from cast manganese steel and having a series of gear teeth upon its periphery, and having also a series of recesses extending outward from its inner surface and into its cast metal body portion, said recesses having each a single opening leading thereinto and the location of said recesses being in line with the teeth aforesaid.

3. Driving means comprising a wrought metal shaft having an enlarged portion circular in cross-section and an annular shell continuous throughout its circumference

secured in place upon said enlarged portion; said shell being formed from cast manganese steel and having a series of gear teeth upon its periphery, and having also a series of recesses extending outward from said enlarged portion into the body of the shell and located in line with the teeth aforesaid, each of said recesses having a single opening leading thereinto.

Signed at Chicago Heights, in the county of Cook, and State of Illinois, this 12th day of June, A. D. 1911.

WESLEY G. NICHOLS.
